UNITED STATES PATENT OFFICE

THOMAS G. WELSH, OF BROOKLYN, NEW YORK

FLEXIBLE TUBE

Application filed October 10, 1930. Serial No. 487,711.

This invention relates to flexible tubes used as containers for paste or other plastic substances of various kinds and classes, wherein the substance employed in the container is discharged from a nozzle end by the flexure or compression of the walls of the container; and the object of the invention is to provide a container of the class specified, the body structure of which is cylindrical in form from the discharge end to the closed bottom wall thereof, thus facilitating the placement of the container in a tubular case or holder of a diameter slightly greater than the diameter of said tube; a further object being to provide a device of the class specified which is comparatively small in size whereby the same may be placed in a pocketbook, vanity case or the like or carried in a pocket of a garment so that the contents of the tube will be accessible for use at all times; a further object being to provide an improved method of constructing the sealed and closed end of tubes of the class under consideration so as to maintain the diameter of the tube throughout the entire length thereof; and with these and other objects in view, the invention consists in a device of the class and for the purpose specified, which is constructed in accordance with the method hereinafter more fully described and claimed.

The invention is fully disclosed in the following specification, of which the accompanying drawings form a part, in which the separate parts of my improvement are designated by suitable reference characters in each of the views, and in which:—

Fig. 1 is a side and sectional view of a container made according to my invention, illustrating the method of forming the closed end wall thereof.

Fig. 2 is a view similar to Fig. 1 showing only a part of the construction, and illustrating the complete formation of the closed end of the container.

Fig. 3 is a perspective view of a closure member which I employ; and,

Fig. 4 is a detail view of one of my improved containers, indicating the method of arranging the same in a case or holder.

In carrying my invention into effect, I pro-

vide a flexible tube 5 which is of conventional form in so far as the structure of the tube proper is concerned, said tube having a flared discharge end 6, terminating in a discharge spout 7, normally closed by a removable cap 8 as in other paint and cream tubes commonly known in the art. The wall of the tube 5 is composed of thin, flexible and compressible material, facilitating the discharge of the

80

contents 9 from the tube. In other tubes of this class, after the contents 9 have been passed into the tube through the open end 10 thereof, the tube is closed by folding said open end upon itself, and it is customary to use a U-shaped clip to seal said end, in which operation, the metal of the tube is flared laterally.

In carrying my invention into effect, after the contents 9 have been placed in the tube, a cup-shaped closure wall 11 is forced upon the contents 9 and disposed in a countersunk relation within the open end 10 of the tube in the manner shown in Fig. 1 of the drawings. The closure 11 is cylindrical in form and has a comparatively wide, peripheral wall 12, which extends outwardly in parallelism to the wall of the tube 5, fitting snugly therein. After the closure wall 11 has been placed in position as shown in Fig. 1, the projecting edge 10a of the tube is turned inwardly and around the wall 12, as seen at 13 in Fig. 2 of the drawings, thus retaining the closure 11 in position and also effecting a seal between said closure and the wall of the tube. The side wall 12 of the closure serves to reinforce the lower or sealed end of the tube 5 as will be apparent.

I also preferably place in the chamber of the closure 11 formed by the wall 12, a filler 14 of any suitable material, preferably one having a wax base although sealing wax, lead and other substances may be employed. The purpose of this filler is to form a flush outer surface to the closed end of the tube and also to aid in reinforcing said end of the tube. It is also preferred that the tube be enclosed in a suitable wrapper or sheet 15 which passes over the lower end of the tube and onto the outer face of the tube to any desired degree

90

85

160

of its length. This outer wrapping sheet need not necessarily be employed.

It will be understood that a tube constructed in the manner above set out will be cylindrical in form and of substantially the same diameter throughout its entire length, thus facilitating the placement of the entire device in a case or holder indicated in dotted lines in Fig. 4 of the drawings, and consisting of a tubular part 16 and a cap 17 detachable with respect to the part 16. The case or holder is constructed of a strong, non-collapsible material so as to prevent flexure of the tube 5 in carrying the same about in a purse, vanity case or in the pocket.

My improved container is adapted primarily for use as a container for paste, creams and other substances that are used from time to time through the day, thus facilitating the convenient carrying of such containers, and at the same time, maintaining a relatively small package as compared with the placement of a tube of conventional form into a case or holder which would be large enough to receive the conventional form of flexible tubes.

It will be apparent that my improved tube may be constructed in very small as well as comparatively large tubes to suit the particular kind and class of product to be marketed therein, as well as to be consistent with the use of the tube. While I have shown certain details of construction for carrying my invention into effect, it will be understood that I am not necessarily limited to these details and various changes in and modifications of the construction herein shown and described may be made within the scope of the appended claims without departing from the spirit of my invention or sacrificing its advantages.

Having fully described my invention, what I claim as new and desire to secure by Letters Patent, is:

1. An article of manufacture of the class described comprising a flexible container tube having a contracted discharge at one end and a removable cap controlling said discharge, said tube beyond the discharge having straight walls and being of the same cylindrical cross section throughout the entire length thereof, a cup-shaped closure member of rigid material arranged within the boundary walls of the other end of the tube and secured thereto, said member opening outwardly through said end of the tube to form a chamber in said end, the side walls of the cup-shaped member extending parallel with and abutting the corresponding walls of the tube, and said cup-shaped member being secured to the tube by folding the second named end of the tube around the peripheral wall of said cup-shaped member, and a filler placed in the chamber of said cup-shaped member, the outer surface of the filler being flush with the second named end of the tube.
2. An article of manufacture of the class

described, comprising a flexible container tube having a contracted discharge at one end and a removable cap controlling said discharge, said tube having straight walls extending from said discharge, a cup-shaped closure member of rigid material fitting snugly within the boundary walls of the other end of the tube and secured thereto, said member opening outwardly through said end of the tube to form a chamber in said end, the side walls of said cup-shaped member being straight and extending parallel with and abutting the corresponding walls of the tube, and means arranged in the chamber of said cup-shaped member and cooperating with the wall of the tube for forming a flush and flat outer surface to said end of the tube and for aiding in supporting said member in the end of the tube.

In testimony that I claim the foregoing as my invention I have signed my name this 9th day of October 1930.
